UNITED STATES PATENT OFFICE.

FRANK D. SHEPHERD, OF AURORA, ILLINOIS.

INTERNAL-COMBUSTION ENGINE.

Application filed December 1, 1919. Serial No. 341,655.

To all whom it may concern:

Be it known that I, FRANK D. SHEPHERD, a citizen of the United States, residing at Aurora, in the county of Kane and State of Illinois, have invented certain new and useful Improvements in Internal-Combustion Engines, of which the following is a specification, reference being had therein to the accompanying drawings.

10 My invention has to do with gas engine construction in so far as it is concerned with valve mechanism, and stated generally, or in brief, my object is to utilize to the maximum the fuel to the extent to which proportion 15 of fuel energy utilized to fuel consumption, is dependent on the valve mechanism, and also to provide a valve mechanism that may be readily and economically manufactured and assembled, and not be subject to 20 arrangement by the conditions under which it operates. To attain my object, my invention consists in the construction substantially as hereinafter specified and defined by or 25 comprehended within the scope of the appended claims.

In the drawings:—

Fig. 1 is a side elevation of the head or upper part of a gas engine, illustrating an embodiment of my invention;

30 Fig. 2 is a vertical section on line 2—2 of Fig. 1;

Figs. 3, 4, 5, and 6 are like views, respectively, of other embodiments of my invention;

35 Fig. 7 is a detail plan view of the twin spring;

Fig. 8 is a detail view, in side elevation of a different form of container construction;

40 Fig. 9 is a detail view showing a form of bushing for detachable head engine that may be used in place of the bushing of the integral head engine of Fig. 4;

Fig. 10 is a detail view in section of a hollow stem that may be used without insulating material;

45 Figs. 11 and 12 are, respectively, detail views, in section, of spring containers and springs that I may employ.

Before proceeding with a description, in detail, of the various embodiments of my

invention shown in the drawings, it is proper to say that my invention is applicable to both L-head and T-head types, to both detachable and integral head engines, and to both intake and exhaust valves. I illustrate both detachable and integral head constructions.

The valve mechanism is of the type shown in numerous of my patents, and briefly described, comprises a poppet valve 10, having a seat 11, that controls a passage 12 in the head 13 that connects the cylinder 14 and a ported chamber 15, a rod or stem 16 that extends upward from the valve, and a coil spring 17, in a shell or container 18, 60 that moves the valve to its seat, following the motion of the usual lifter cam, (not shown). The stem 16 passes through a guide hole 19 that passes through the head 13 from the interior of the container, which 65 hole may be directly in the head itself, as shown in Fig. 2, or through a bushing, shown in Figs. 3, 4 and 5, and hereafter described.

Within the container the stem has an enlargement which may be an integral head 70, as in Figs. 2 and 4, or a separate head 21, as in Figs. 3 and 5, that has a socket in its underside and fits upon the top of the stem.

75 The stem 16 may be separate from the valve, as in Figs. 2 and 4, or integral therewith, as in Figs. 3 and 5.

It is of high importance that the stem be as light as possible to assure quick movement to effect prompt seating of the valve, and that the transmission of temperature to the interior of the container apt to injure the spring, be prevented. I accomplish this two-fold result by the single expedient of making the stem hollow and placing within it a heat-insulating material of less specific gravity than the metal of the stem, such as asbestos, for example. As shown in Figs. 2 and 3, the hollow, or chamber 22 extends from the top of the stem nearly to the bottom, and the filling 23 is asbestos, mineral wool, etc. The top of the chamber is closed or sealed by the spring engaging disk or head 21, in Fig. 3, and 100

by a thin cap or disk 24, in Figs. 1 and 6, to prevent the asbestos shaking out from the motion of the stem.

In Figs. 4 and 5, the tubular stem is filled with graphite or mica compounds or other lubricating and lightening material 25, and it has radial holes 26 through which the material reaches to the exterior of the stem, and thus supplies lubricant thereat. I employ a material that has a higher coefficient of expansion than the metal of the stem so that on being heated, it expands more, and forces the lubricant into close contact with the surface of the guide hole. The lifting stem 29 in Fig. 5 is also hollow and filled by lubricating and lightening material, and it has like radial holes 290 and its end next the valve is closed by a cap 291.

If desired, both the lifting and seating stems may be merely hollow, with no filling, as shown in Figs. 3 and 10, but vented to allow the escape of heated and expanding air, or gas.

The hollow seating stem, when empty or not filled with a heat insulator, should have its portion that is outside the guide, when the valve is seated, and which is exposed to the high temperatures, solid, as shown in Figs. 6 and 10, and as shown in Figs. 4 and 5, so that hot tube action will be avoided. The hollow part that is within the guide is protected by the water jacket around the guide.

A small vent hole or opening is provided in the disk 21 and the cap 24 to permit the escape of air or gas as the volume thereof is increased due to the high temperatures, so as to avoid any swelling of the stem from the pressure by the increase of volume that might cause the stem to bind in its guide.

The bushing 30 of Fig. 3 is a simple flangeless tube, tightly fitting an opening in the engine head that may be a sponge casting impregnated with a frictionless material, which, especially in the case of marine engines, may be graphite, or other material that will protect the stem from the corrosive effect of salt water or air, or, if preferred, the bushings 31 shown in Figs. 4 and 9 may be used that have a flange 32 at their outer ends that overlap the contiguous surface of the engine head, and are engaged on the outer sides by the lower end of the spring container 18, which may have an internal annular groove 33 to receive the flange 32, as shown in Fig. 4, or the flange may have an annular groove 34 to seat the bottom of the container, as in Fig. 9. In Fig. 4 the engine is an integral head one and the hole filled by the bushing is large enough for the passage of the valve, while the bushing shown in Fig. 9 is for a detachable head, which has a smaller bushing hole in it, although the hole might be as

large as in Fig. 4 for the removal of the valve without removing the head itself.

In Figs. 5 and 11, the bushing 35 is integral with the container and in Figs. 6 and 12 it is in the form of a cylindrical block 70 or plug 36 that is secured by radial pins 37 to a downward extension 38 of the bottom of the container.

It will be noted that in all the forms of my invention shown in Figs. 2 to 12, (except Fig. 8) there is no threaded connection between the container and the engine head, but the container simply enters a socket within a flange 39 in the top of the head, as in Fig. 2, or fits over a boss 40 as in Fig. 3, or over the flange of the bushing, as in Fig. 4, or has a reduced extension of its bottom that enters a hole in the engine head, as in Figs. 6, 11 and 12. Dispensing with screw threads enables me to make the walls of the parts involved, thinner than is possible where thickness to permit thread to be cut is necessary.

Dispensing with a threaded connection of the container and head, I employ a clamping device of the type shown in Figs. 1, 2, 3, 4, 5, 6 and 8, to hold the container with the desired tightness against the engine head. Said device is in the form of a yoke 41, that extends above each container as in Fig. 3, or a row of them as in Fig. 1, and is strongly bolted to the engine head, and which has a set screw 42 that bears against a pressure distributing disk 43 applied to the closed head of the container, the set screw having a lock nut 44. The container head may be integral, as in Figs. 2, 3, 4, 6, and 12, or a separate cover 45, as in Figs. 5, 8 and 11 which has a flange that slips over the container, as in Fig. 5 or a separate cover 46, as in Figs. 8 and 11 that slips in the open end of the container. Gas-tight conditions at abutting surfaces are secured by gasket or ground joints.

The container construction shown in Figs. 6 and 8 permits of all parts being assembled away from the engine, except the clamping device, and hence, is a form that may be handled and sold as an accessory.

In Fig. 8, I show the clamp device fitted to hold only the separate cover 46 upon the container, the yoke 48 catching under a flange 49 on the container, and the screw 50 bearing against the cover. The container, in this case, has a threaded extension 47 from its bottom by which it is attached to the engine head.

The lower portion of the stem 16 is preferably, as shown in Figs. 4, 5, 6 and 10, reduced in diameter from a point at or just below the bottom of its guide hole, when the valve is seated. This provides a sharp shoulder 160 that scrapes off any carbon or other deposits at the bottom portions of

the guide hole, and when the stem lifts into the guide hole, an ample space exists between it and the guide hole, and thus sticking of the stem by an accumulation of 5 carbon, is prevented as well as from expansion of the lower part of the stem from the high temperatures to which it is exposed in the combustion chamber. To give a good wide bearing of the stem against the 10 valve, it may have a head or enlargement 161 at its valve-engaging end, as shown in Figs. 4 and 6; or when that is not required the head may be omitted, as in Fig. 10. The reduced part of the stem may be either 15 tapering, as shown in Figs. 5, 6 and 10; or cylindrical as shown in Fig. 4.

I may use a single spring in the container as shown in Figs. 2, 3, 4 and 5, or as shown in Figs. 11 and 12, a plural number of 20 springs 51 may be used, placed, for example, one within the other and acting simultaneously to seat the valve, and of the same pitch, as shown in Fig. 12, or of opposite pitch, as shown in Fig. 11.

25 I have discovered that a coil spring tends to buckle in the direction away from the bearing point of the end of the spring, and thus an unbalanced pressure is exerted on the valve. When I use two springs, I place them so that their bearing points are opposite, and hence the tendency of one to buckle in one direction and its effect on the valve, is opposed and neutralized by the other. To prevent any displacement of the springs 30 from this relative position I may secure them thereat as by a teat or lug 510 on the end that enters a hole in the part engaged by the spring, which, preferably, is not the stem head or disk, as I desire the conditions to be such as to leave the valve free 35 to rotate relative to its seat to avoid localized wear. The function of the spring ends on the part they engage will in some cases, especially as the finished ends are more or 40 less sharp or pointed and extend in opposite directions, be to prevent relative rotation thereof. The plural spring idea may be carried out, as shown in Fig. 6, where there are two springs 52 that are duplicates 45 or twins, the coils of both being the same diameter and they adjoin in the direction of the axes of the springs, and not transversely thereof, as in Figs. 11 and 12, where one is smaller in diameter than and is surrounded by the other. The terminals of the 50 twin springs at the same end of the spring are arranged diametrically opposite in accordance with the principle of the same arrangement in Figs. 11 and 12. Some of 55 the advantages of the twin springs are that together they have the pressure-exerting strength of a single spring, without the objectionable thickness of wire a single spring would have, for together the twin springs 60 may be of a gage to equal the strength of

such a single spring; and as they are of the same diameter, each perfectly opposes any buckling tendency of the other. Again, as in dual valve engines the valves are small and set close together, the plural spring 70 idea cannot be well carried out if one spring surrounds another because the internal diameter required of the container to take them could not be made small enough to suit the space limitations. With the twin 75 spring arrangement that difficulty is overcome, since both springs are of the same diameter. It is not necessary with the twin springs to provide any locking device, such as hole-engaging teats or lugs, to preserve 80 their relative position, because the close lapping of the coils of one on the other at the ends serves that purpose.

The twin spring arrangement is applicable to other types of valves than my 85 spring-container type, and I embrace other types within the scope of my claims where the language thereof warrants.

I claim:—

1. The combination of an internal combustion engine having a port, of a valve for closing the port, a hollow valve stem that bears against the valve and is separate therefrom, and means operating against the stem for actuating the valve. 90

2. A valve mechanism for internal combustion engines, comprising a valve, a hollow stem for the valve, said stem having a filling of heat insulating material, and means that operates on the stem for actuating the valve and is protected by the heat insulating material. 100

3. The combination in an internal combustion engine having an explosion chamber and a port, of a valve for the port, a container, a stem reaching from the container across the explosion chamber to the valve, hollow for a portion of its length and solid for the portion of its length contiguous to the valve, and a spring in said container acting on the stem. 105

4. A valve mechanism for internal combustion engines, comprising a valve, a spring container, a hollow stem reaching from the interior of the container to the valve and having a filling of light heat insulating material, and a spring in the container operating on the stem material. 115

5. A valve mechanism for internal combustion engines, comprising a valve, a container, a hollow stem reaching from the interior of the container to the valve, having a vent opening into the container, and a filling in the stem. 120

6. The combination in an internal combustion engine having a plurality of ports, of valves controlling the ports, a plurality of containers in the engine, valve actuating means in the containers, a yoke extending over the various containers, and clamping 125 130

means between the yoke and the various containers, the clamping means of the various containers being independently operable.

7. The combination in an internal combustion engine having a plurality of ports, of valves controlling the ports, a plurality of containers in the engine, valve actuating

means in the containers, a yoke extending over the various containers, and screws in the yoke that bear respectively against the 10 containers.

In testimony whereof I affix my signature.

FRANK D. SHEPHERD.
